PRODUCTION OF MOTOR FUELS

Robert Bartlett Ewell, Chicago, Ill., assignor to
Universal Oil Products Company, Chicago, Ill.,
a corporation of Delaware

Application April 30, 1940, Serial No. 332,428

6 Claims. (Cl. 196—10)

This invention relates to a process wherein volatile gasolines are converted by a number of treatment steps to substantial yields of high octane gasoline with increased boiling point and containing principally isoparaffins and derivatives of aromatic hydrocarbons.

The purpose of this invention is to convert highly volatile gasoline such as natural gasoline, containing comparatively large proportions of butanes and pentanes, into more useful products boiling in the gasoline range. Simultaneously, it is desired to improve the antiknock properties of the gasoline.

This invention comprises a combination of the treatment steps of isomerization, dehydrogenation, alkylation of isoparaffins, alkylation of aromatic hydrocarbons and aromatization.

More specifically, this invention comprises fractionation of the gasoline to be treated into: (1) heavy fraction containing principally C₆ or higher hydrocarbons; (2) a fraction containing substantially all the normal pentane; (3) a fraction containing all the isopentane; (4) a normal butane fraction and (5) a fraction consisting principally of isobutane. The normal pentane fraction is passed through the isomerization step, the hydrocarbon products from which are returned to the original separating zone. Employing a recycling operation, all original pentane is converted into isopentane. This isopentane may be (a) charged to an alkylation step, (b) blended with the finished gasoline or (c) stored for further blending with gasolines from other sources.

The normal butane fraction is entirely or in part contacted with a dehydrogenating catalyst and after removing ethane and lighter products, is used in alkyinating isoparaffins and aromatics. If the quantity of aromatic hydrocarbons and isoparaffins to be alkylated is relatively large, all of the normal butane obtained from the original charging stock may be dehydrogenated. In some cases, however, where the charging stock contains a large quantity of normal butane it may be found desirable to subject a portion of the normal butane to an isomerizing step to form isobutane. The isobutane present in the charging stock together with that which may be formed in the isomerizing process is alkylated with olefins obtained principally in the dehydrogenation of normal butane. The C₆ and higher hydrocarbons obtained from fractionation of the charge are contacted with an aromatization catalyst after which ethane and lighter products are removed. The unreacted paraffins and the olefins formed in the dehydrocyclization step are separated from the aromatic hydrocarbons by fractional distillation, by solvent extraction or by a combination of the two methods. The unreacted paraffins and the olefins formed in the aromatization process are recycled to the aromatization catalyst. The

aromatic hydrocarbons obtained by the methods mentioned above are alkylated by the propylene and butenes obtained in the catalytic dehydrogenation step already referred to. It is a feature of this process that any propane formed in the reactions together with unreacted normal butane is recycled to the dehydrogenation stage.

The solvent extraction step used in separating aromatic hydrocarbons from the other products of the aromatization step may utilize such well known solvents as liquid SO₂, furfural, methyl carbitol, etc.

In one specific embodiment the invention comprises fractionating volatile saturated gasoline in commingled state with the hydrocarbon conversion products formed in the isomerizing steps as hereinafter described to separate isobutane, normal butane, isopentane, normal pentane and higher boiling hydrocarbons, commingling said higher boiling hydrocarbons with a recycle stock of paraffins and olefins obtained in a manner to be subsequently described and subjecting said mixture to a catalytic aromatization process, separating the conversion products from said aromatization process into a fraction composed of hydrogen, methane and C₂ hydrocarbons, a fraction comprised essentially of aromatic hydrocarbons, a fraction consisting essentially of paraffins and olefins containing three or four carbon atoms per molecule and a fraction consisting principally of unreacted paraffins and olefins with C₆ and higher boiling hydrocarbons separated from the charging stock to form the combined feed for the aromatization step as hereinbefore set forth, commingling the aforesaid aromatic hydrocarbons separated from the products of the aromatization step with C₃ and C₄ hydrocarbons obtained from the butane dehydrogenation step to be subsequently described, directing said mixture of aromatics and olefin-containing hydrocarbons to an alkylation zone for catalytic alkylation of the aromatic hydrocarbons with propene and butenes to form alkylated aromatic hydrocarbons of the motor fuel boiling range, separating said alkylated aromatic hydrocarbons from the unreacted propane and butane, simultaneously catalytically isomerizing normal pentane separated from the charging stock into isopentane, catalytically dehydrogenating a portion of the normal butane obtained from the charging stock, isomerizing the remainder of said normal butane into isobutane, commingling said isobutane with the isobutane separated from the charging stock and catalytically alkylating the combined isobutane fractions with propylene and butenes obtained in the butane dehydrogenation step to form a saturated product substantially of motor fuel boiling range, separating from the products of the alkylation step alkymer and reacted propane and normal butane, commingling said unreacted

propane and normal butane into propane and normal butane separated from the aromatic alkylation process with the normal butane obtained from the charging stock and directing said mixture to the butane dehydrogenation step as hereinbefore set forth.

The process is illustrated in the accompanying flow diagram which shows the relationship between the various steps comprising the invention.

Referring now to the diagram, the charge which may comprise a volatile gasoline such as a natural gasoline, is introduced by way of line 1 to separation zone 2. Separation zone 2 comprises a series of fractionating columns wherein the charging stock is fractionated jointly with the hydrocarbon conversion products of the isomerization steps. The normal butane obtained in separation zone 2 is removed by way of line 3 from which a portion or all may be directed through line 4 to dehydrogenation zone 5.

The dehydrogenation is accomplished in the presence of a catalyst which consists in general of pellets or granules of alumina or inert siliceous or refractory materials composited with compounds, and preferably the oxides, selected from the elements of the left-hand columns of groups IV, V and VI of the periodic table. Although the dehydrogenation catalysts disclosed above are the preferred catalysts, they are not to be considered as a limiting feature, for other catalysts capable of effecting dehydrogenation known to those skilled in the art may be employed in the broad scope of the invention. Dehydrogenating temperatures are ordinarily in the range from 900-1200° F., while employing a pressure ranging from substantially atmospheric to a hundred or more pounds per square inch superatmospheric.

The products of the dehydrogenation treatment in zone 5 are directed through line 6 into separation zone 7 wherein hydrogen and light gases such as methane and the C₂ hydrocarbons are substantially separated from the dehydrogenated products and withdrawn through line 8.

If so desired, a portion of the normal butane may be removed from line 3 by way of line 9 and directed to isomerization stage 10 for conversion into isobutane. As there may be changes in the composition of the charging stock there will necessarily be corresponding modifications in the proportions of materials directed to the various steps in the process. Catalysts used in the isomerization process normally include anhydrous aluminum chloride with or without an inert support. In some cases it may be found advantageous to use mixtures of anhydrous chlorides of other elements in conjunction with the aluminum chloride. Chlorides that have been found effective in such combination include those of zinc, zirconium, iron and copper. It has also been found advantageous in the isomerization process to introduce anhydrous hydrogen chloride as well as elementary hydrogen along with the charging stock. The amount of hydrogen chloride introduced usually lies within the approximate range of 0.5 to 10% by volume of the normal butane. It has been found that saturating the normal butane fraction with hydrogen gas at room temperature and under a pressure within the approximate range of 25 to 100 atmospheres produces beneficial results. The normal butane is contacted with a catalyst at a temperature within the approximate range of 50-350° C. and pressures varying from substantially atmospheric to approximately 200 atmospheres may be used. The reaction of the isom-

erization of normal butane to isobutane is never complete under the conditions of operation and the mixture of normal butane and isobutane obtained is directed by way of line 11 to line 16 from which it is returned to separation zone 2 wherein the isobutane is fractionated from the normal butane. The hydrogen and hydrogen chloride used in the isomerization process may be recovered by methods well known and reused in the process. These recovery steps are not shown in the flow diagram. The isomerization of normal butane is always accompanied by the formation of both lighter and heavier products such as propane and pentane. Any propane formed in the isomerization step may be commingled with the charging stock for the dehydrogenation zone 5.

The isobutane separated from the stock together with that formed in isomerization is removed from separation zone 2 by way of line 12 from which it is directed by way of line 17 to line 18 for commingling with the propylene- and butylene-containing gases obtained from the separation zone 1 following the dehydrogenation process.

The mixture of isobutane and olefin-containing gases in line 18 is directed to the alkylation zone 19 for alkylation of isobutane to higher molecular weight isoparaffins.

The normal pentane separated from the charging stock in zone 2 is removed by way of line 14 and directed to the pentane isomerization zone 15. Catalysts used for isomerizing normal pentane are substantially the same as those used in isomerizing normal butane. In some cases, it may be desired to isomerize normal pentane and normal butane in the same zone, although in general separate zones will give more selective results. The temperatures used in the isomerization of normal pentane usually lie within the approximate range of 50-250° C. Pressures within the range of 100-200 atmospheres may be used. The addition of hydrogen and anhydrous hydrogen chloride in approximately the same quantities as used in the butane isomerization step may be used here. A small amount of propane and butanes are formed in the pentane isomerization step. The propane separated from the pentane isomerization step may be added to the charge for dehydrogenation zone 5, although this is not shown in the diagram. The mixture of pentanes is removed from the isomerization zone 15 by way of line 16 and is separated in separation zone 2.

The isopentane separated from the charging stock as well as that formed in the isomerization step is removed from separation zone 2 by way of line 13 from which it is directed to line 18 for commingling with the dehydrogenation products obtained from separation zone 1. The mixture of isopentane and olefins is directed from line 18 to alkylation zone 19. The catalysts used in the alkylation of isoparaffins with olefins may comprise concentrated sulfuric acid, hydrogen fluoride, aluminum chloride with hydrogen chloride and phosphoric acid either in liquid form or in the form of a solid composite with a siliceous adsorbent. When using sulfuric acid, temperatures within the range of 15-100° F. are commonly employed. Sufficient pressure is maintained in the system to keep the reactants in liquid state. In order to reduce as far as possible the reactions of polymerization, acids of a concentration above 88% are commonly used. It is also necessary to maintain a high ratio of iso-

paraffins to olefins in the alkylation reaction zone. Ratios of isoparaffin to olefin lying between 80:1 and 20:1 give satisfactory results. According to the flow diagram isobutane and isopentane are alkylated in the same zone. If desired, separate alkylation zones may be used for isobutane and isopentane, although such procedure is not necessary. The products of the alkylation zone are removed by way of line 20 and directed to a fractionation step 21. Since propane and normal butane are practically inert under the conditions of alkylation used, they are removed by way of line 22 and directed to line 3 for subsequent dehydrogenation to the corresponding olefins. The excess isobutane and/or isopentane separated in zone 21 is removed by way of line 23 and recycled to the alkylation zone. The alkymer product which consists principally of isoparaffins of the motor fuel boiling range is removed from the alkylation zone by way of line 24 and directed to storage 25. It may be subsequently redistilled to remove the small proportion of material boiling above the gasoline boiling range. In some cases it may not be desired to alkylate all the isopentane and a portion may be removed by way of line 13 to line 26 and directed to storage 25. Isopentane has a high antiknock value and may be disposed of as such or may be blended with gasolines to produce the desired vapor pressure and antiknock requirements.

The higher boiling paraffins separated from the charging stock in zone 2 consist principally of hexane, heptane and octanes and are directed by way of line 26 and after commingling the recycled charge of paraffins and olefins directed to aromatization zone 27.

Catalysts used in the aromatization process may comprise alumina or other relatively inert carrier composited with an element selected from the group consisting of elements in the left-hand columns of groups 4, 5 and 6 of the periodic table. Temperatures used in the aromatization process lie within the approximate range of 850-1200° F. and pressures varying in the approximate range of atmospheric to 100 or more pounds are used. The conversion products of the aromatization process consist of aromatic hydrocarbons, unreacted paraffins, their corresponding olefins, hydrogen and small quantities of light hydrocarbons. These conversion products are directed by way of line 28 to separation zone 29. The hydrogen, methane and C₂ hydrocarbons separated in zone 29 are removed from the system by way of line 30. Separation zone 29 may comprise a series of fractionating columns for separation of aromatic hydrocarbons from paraffins and olefins. The boiling points of paraffins such as normal hexane are usually 10-12° C. below that of the corresponding aromatic hydrocarbon such as benzene. Such differences in boiling point are sufficient to obtain necessary separation by distillation methods. It may be preferred, however, to use such selective solvents as SO₂, furfural, carbitol and others. The unreacted paraffins and the corresponding olefins are separated in zone 29 or directed to line 31 from which they are recycled to the aromatization zone. The aromatic hydrocarbons are removed from separation zone 29 by way of line 32 and are commingled with propylene- and butene-containing gases separated from dehydrogenation zone 5 in zone 7 from which they are removed by way of line 33. The mixture of

aromatic hydrocarbons and olefin-containing gases is directed to alkylation zone 34.

The aromatic hydrocarbons are alkylated with the olefins in the presence of suitable catalysts such as sulfuric or phosphoric acid, solic phosphoric acid, metal halides such as aluminum chloride, hydrogen fluoride, boron trifluoride or mixtures of hydrogen fluoride and boron trifluoride. When using sulfuric acid, concentrations of about 84 to 100% are employed. The so-called solid phosphoric acid catalysts consist of a composite of liquid phosphoric acid with kieselguhr or similar suitable siliceous materials. Metal halides employed should be substantially but not completely anhydrous. The temperatures used in the alkylation step depend upon the catalyst, its concentration, etc., and cover a range of approximately -35 to 200° F., but are usually within the range of 50-150° F. The pressures may extend up to 500 pounds per square inch or higher and are normally sufficient to maintain the gaseous olefins used in substantially liquid phase.

The reaction products from alkylation zone 34 are passed through line 35 to separation step 36. The C₃ and C₄ paraffins present in the olefin-containing gases for the alkylation process are removed from separation zone 36 by way of line 37 from which they are directed to line 3 for recycling to the butane dehydrogenation zone. The alkylated aromatic hydrocarbons, together with small amounts of unreacted aromatics are removed from separation zone 36 by way of line 38 and sent to storage 25. These alkylated aromatic hydrocarbons lie within the gasoline boiling range and may be blended with isopentane or the isoparaffins formed in alkylating isobutane or isopentane.

The following example will illustrate the results obtainable by the process described in my invention. The following results are based upon a charging stock of east Texas natural gasoline having the properties shown in Table I.

TABLE I
East Texas natural gasoline—1000 pounds

Octane number: 83
Reid vapor pressure: 26

	Pounds	Volume percent
1-Butane	18	2.0
n-Butane	298	31.9
1-Pentane	219	21.9
n-Pentane	203	20.0
Hexane	171	16.1
Heptane	56	5.1
Octane	34	3.0

TABLE II
Summary of yields

Variation	Volume percent yield of gasoline	Octane number	Reid vapor pressure
1	73.0	83	7
2	74.2	85	6
3	75.6	86	6
4	76.7	88	11

The four examples cited differ partially in the proportion of isopentane alkylated and the proportion of normal butane isomerized to the iso derivative. The particular proportions directed to the various streams will depend in part upon the volatility desired in the final product.

I claim as my invention:

1. A process for producing more valuable products from volatile saturated gasoline which comprises fractionating the gasoline to form a light fraction containing normal butane and a heavier fraction containing hexane and higher boiling hydrocarbons, subjecting said light fraction to dehydrogenation to produce olefins therefrom, subjecting said heavier fraction to aromatization to form aromatics, commingling the latter with at least a portion of said olefins, subjecting the resultant mixture to alkylation to react olefins with aromatics, and recovering the alkylated aromatics thus formed.

2. The process as defined in claim 1 further characterized in that there is additionally separated from said gasoline an iso-paraffin fraction of lower boiling point than said heavier fraction, said iso-paraffin fraction being commingled another portion of said olefins from the dehydrogenating step, the mixture subjected to alkylation and resultant alkymer blended with said alkylated aromatics.

3. The process as defined in claim 1 further characterized in that there is additionally separated from said gasoline an iso-butane fraction which is commingled with another portion of said

olefins from the dehydrogenating step, the mixture subjected to alkylation and resultant alkymer blended with said alkylated aromatics.

4. The process as defined in claim 1 further characterized in that there is additionally separated from said gasoline an iso-pentane fraction which is commingled with another portion of said olefins from the dehydrogenating step, the mixture subjected to alkylation and resultant alkymer blended with said alkylated aromatics.

5. The process as defined in claim 1 further characterized in that there is additionally separated from said gasoline a normal pentane fraction which is subjected to isomerization and resultant iso-pentane blended with said alkylated aromatics.

6. The process as defined in claim 1 further characterized in that there is additionally separated from said gasoline a normal pentane fraction which is subjected to isomerization and the resultant isopentane commingled with another portion of said olefins from the dehydrogenating step, the mixture subjected to alkylation and the resultant alkymer blended with said alkylated aromatics.

ROBERT BARTLETT EWELL.
